DRESSER OR SIMILAR ARTICLE

Donald A. Wallace, Washington, D. C., and David Bendersky, Kansas City, Mo.; said Bendersky assignor to Midwest Research Institute, Kansas City, Mo., a corporation of Missouri

Application January 7, 1950, Serial No. 7,052

Term of patent 14 years

(Cl. D33—6)

To all whom it may concern:

Be it known that we, Donald A. Wallace and David Bendersky, both citizens of the United States, and residents of the city of Washington, District of Columbia, and of the city of Kansas City, in the county of Jackson and State of Missouri, respectively, have jointly invented a new, original, and ornamental Design for a Dresser or Similar Article, of which the following is a specification, reference being had to the accompanying drawing, forming a part thereof.

On the drawing:

The characteristic features of our design are shown in full lines.

We claim:

The ornamental design for a dresser or similar article, as shown and described.

DONALD A. WALLACE.
DAVID BENDERSKY.
